UNITED STATES PATENT OFFICE.

HARRY LEE AND EDWARD H. HANSEN, OF LIVINGSTON, MONTANA.

CONTINUOUS DRAW-BAR.

1,320,011.

Specification of Letters Patent. Patented Oct. 28, 1919.

Application filed January 13, 1919. Serial No. 270,905.

To all whom it may concern:

Be it known that we, HARRY LEE and EDWARD H. HANSEN, citizens of the United States, residing at Livingston, in the county 5 of Park and State of Montana, have invented certain new and useful Improvements in Continuous Draw-Bars, of which the following is a specification.

The invention relates more particularly to 10 draft rigging for freight cars, the purpose being to facilitate inspection of the draft rigging and to reduce the wear and tear to the smallest amount possible, thereby preventing the frequent pulling out of draw- 15 bars and the delay and expense incident to making temporary and permanent repairs.

In accordance with the present invention, a continuous drawbar is mounted upon the framework or under structure in a manner 20 to receive a limited longitudinal movement, said continuous drawbar consisting of a sectional tube having drawbars at opposite ends and containing the drawbar springs which sustain the draft and the buffing action when 25 the cars are run together for coupling.

The drawing illustrates a preferred embodiment of the invention; however, it is to be understood that in adapting the same to meet different conditions, various changes in 30 the form, proportion, and minor details of construction may be resorted to without departing from the nature of the invention as claimed hereinafter.

Referring to the drawing hereto attached, 35 Figure 1 is a top plan view of the under frame of a freight car and a drawbar mounted thereon embodying the invention.

Fig. 2 is a central longitudinal section.

Fig. 3 is a side view of the sectional tube, 40 the draw-bars being omitted.

Fig. 4 is a side view of an end portion of the inner or main tube.

Fig. 5 is a longitudinal section of an end portion of the continuous drawbar.

Fig. 6 is a detail section on the line 6—6 of Fig. 5.

Fig. 7 is a detail view of one of the reinforcing plates at the outer end of the outer tube.

Fig. 8 is a cross section on the line 8—8 of Fig. 1 looking to the left as indicated by the arrow.

Corresponding and like parts are referred to in the following description and indicated 55 in the several views of the drawing by like reference characters.

The under frame of a freight car comprises end sills 1, transoms 2, cross beams 3, corner braces 4 and truss rods 5, the latter passing under the beams 3 through the transoms 2 and adapted to be connected at their ends with the sills 1. The under frame likewise comprises side sills 6 and intermediate sills 7 and 8, the several sills being connected with the cross members in any 65 preferred manner.

The continuous drawbar comprises an inner tube 9 and outer tubes 10 which are telescopically mounted upon end portions of the inner tube 9. For convenience the inner tube is formed of two sections which are coupled by means of a sleeve 11, keys 12 passing through registering openings formed in the sections of the inner tube 9 and sleeve 11. The continuous drawbar is mounted on 75 the cross beams 3 and transoms 2 so as to receive a limited longitudinal movement and is somewhat less than the distance between the end sills 1 to admit of a limited longitudinal movement thereof in each direction. 80 The outer tubes 10 project beyond the ends of the inner tube 9 and the projecting ends have draw-bars 13 coupled thereto by means of keys 14. The projecting ends of the tubes 10 are reinforced by means of side plates 15 and a bottom plate 16, said plates being disposed within the tubes and secured thereto by fastenings which are counter-sunk so as not to offer any projecting parts. The side plates 15 are formed with openings 17 to 90 receive the key 14 and sustain the major portion of the pulling and backing strain and prevent the key 14 from enlarging the openings formed in the sides of the tubes 10. The bottom plate 16 forms a rest and sus- 95 tains the wear incident to the lateral movement of the draw-bar.

Each end of the inner tube 9 and each of the outer tubes 10 are of like formation and receive corresponding parts, hence a 100 detailed description of one will suffice for a full understanding of both ends of the continuous drawbar and concomitant parts. The tube 9 is formed with slots 18, 19, 20, 21 and 22. The slots 19 are relatively short 105 whereas the remaining slots are relatively long to provide for movement of the keys passing therethrough. The outer tube 10 is formed with slots 23, 24, 25, 26, 27, 28 and 29. The slots 24, 26 and 27 are relatively 110 long whereas the remaining slots are relatively short. Keys 30, 31, 32, 33, 34, 35, and

14 pass through the respective slots 18—23, 19—24, 20—25, 21—26, 22—27, 28 and 29. Within the tube 9 is located draw-bar springs of standard size, it being understood that the tube 9 is of a size to receive the standard draw-bar springs and the tube 10 is of a size larger than the tube 9 to telescope thereon, the several tubes being preferably of steel and of such construction as to withstand the usage to which they will be subjected when in service. The draw-bar springs 36, 37, 38, 39, 40 and 41 are disposed between the keys 30, 31, 32, 33, 34, and 35, plates 42 being disposed between the ends of the springs and the keys to evenly distribute the strain. The keys 30, 32 and 35 are received in the short slots of the tube 10 and move longitudinally with such tube and the keys 30 and 32 pass through the long slots of the tube 9, thereby admitting of the outer tube having a relatively longitudinal movement on the inner tube. The key 31 is received in the short slots 19 of the tube 9 and passes through the long slots 24 of the outer tube 10. The key 35 is received in the short slots 28 in the sides of the tube 10 and being clear of the inner tube 9 is movable relatively thereto. The continuous drawbar is so arranged that the keys 33 and 34 are disposed upon opposite sides of the transoms. Movement of the drawbar to the right brings the key 33 at the right hand end of the drawbar against the inner side of the adjacent transom 2 and the key 34 at the left hand end into contact with the outer side of the adjacent transom, thereby resulting in compressing the springs at the left of the respective keys 33 and 34. A movement of the drawbar to the left brings the keys 33 and 34 to the right of the transoms contiguous thereto into contact with the transoms, thereby resulting in compressing the springs to the right of the respective keys 33 and 34. It will thus be understood that the drawbar having a relative longitudinal movement to the under frame and the arrangement being such that the pulling and backing strain is imparted to the drawbar, shock is prevented by reason of the buffer action of the spring connection between the drawbar and the under frame. This cushioning of the strain materially reduces the wear and prevents the pulling out of the draw-bars. By having the inner tube 9 made in sections either end portion of the drawbar may be removed, repairs made and

replaced without disturbing the opposite end portion of the drawbar. 60

The foregoing description and the drawings have reference to what may be considered the preferred, or approved, form of our invention. It is to be understood that we may make such changes in construction and arrangement and combination of parts, materials, dimensions, et cetera, as may prove expedient and fall within the scope of the appended claims. 65

Having thus fully described our invention, 70 what we claim as new and desire to secure by Letters Patent is:—

1. In draft rigging for railway cars, a draft line comprising a tube, draw-bars connected to the ends of the tube and a bottom reinforcing plate and side reinforcing plates secured within the tube and adapted to sustain the wear and strain. 75

2. In draft rigging for railway cars including an under frame, a longitudinally movable inner tube supported by the under frame and extending approximately the full length thereof, short outer tubes mounted on opposite end portions of the inner tube and movable thereon, the inner and outer tubes having corresponding slots in opposite sides, certain slots being relatively short and others long, keys passing through the slots, springs within end portions of the inner tube and confined between adjacent 90 keys and adapted to cushion the draft in each direction, and drawbars at the outer ends of the short tubes. 80

3. In draft rigging for railway cars, an under frame comprising longitudinal sills 95 and connecting end sills and transoms, an inner tube extending approximately the full length of the under frame and supported in the transoms to move longitudinally, short outer tubes slideable on end portions 100 of the inner tube through the said transom, the inner and outer tubes having corresponding slots in opposite sides, certain slots being relatively short and others long, keys passing through the slots, two of the keys 105 being disposed upon opposite sides of the respective transoms, and springs within end portions of the inner tube and between adjacent keys. 105

In testimony whereof we affix our signatures in presence of two witnesses. 110
